Patented Jan. 19, 1915.

UNITED STATES PATENT OFFICE.

GEORGE C. CARD AND WILLIAM MYERS, OF SEATTLE, WASHINGTON.

WINCH.

1,125,813.

Specification of Letters Patent.

Patented Jan. 19, 1915.

Application filed February 3, 1913. Serial No. 745,982.

To all whom it may concern:

Be it known that we, GEORGE C. CARD and WILLIAM MYERS, both citizens of the United States, residing at Seattle, in the 5 county of King and State of Washington, have invented a certain new and useful Improvement in Winches, of which the following is a specification.

Our invention relates to improvements in 10 winches; and the object of our improvement is to provide a winch that shall be adapted easily to pull, haul, hoist or move, a body when but little power is applied to operate such winch for the required time; and which 15 will be simple in its plan of construction and have great capability in proportion to its size and weight; and which, further, shall be so constructed that in its operation the two portions of a loop of a cable that 20 may extend from it shall be disposed substantially in the same vertical plane whereby a man or animal readily may step over the two portions of its loop of cable or its two cables at the same time. We attain 25 this object by devices illustrated in the accompanying drawings, wherein—

Figure 1 illustrates a winch embodying our invention by a view in side elevation wherein some of its parts are shown in 30 a vertical-section, Fig. 2 is a plan view of a portion of the same with certain parts removed which parts are shown in Fig. 1 as being disposed above broken line α , α , Fig. 3 is a perspective view of a fragment of a 35 detail of the same, Fig. 4 is a like view of another part of the same, Fig. 5 is a plan view showing a form of two associated gear-wheels embodied in our invention, Figs. 6 and 7 are perspective views of details, of 40 our invention and Fig. 8 is a plan view showing associated parts of our invention and their relative positions.

Like reference numerals indicate like 45 parts throughout the drawings.

Referring to the drawings, two shafts 9 and 10 respectively are disposed vertically in 50 to be rotatable within suitable bearings in a supporting frame comprising a bed-plate 11, a top-plate 12, a connecting brace 13 and brace-rods 14, 14.

Mounted rigidly on shaft 9 and extending 55 between the upper-plate 12 and the bed-plate 11 is a winding-drum 17 provided with a lower flange 15 and an upper flange 16. The lower flange 15 is provided with a hole 55 within which is disposed a hook 18 whose

sleeve 19 is secured to the end of that portion of a cable 20 which is wound around the lower portion of the winding-drum 17, which cable 20 leads from the winding-drum 17 to and through a pulley-block 21 which is secured by a strap 22, hook 23 and rope 24 to a stump 25, and from pulley-block 21 the other end portion of cable 20 leads to and is wound upon another winding-drum that is mounted upon the shaft 10 and provided with an upper flange 26 and a lower flange 27.

The upper side of each of the flanges 16 and 26 is provided with a toothed ratchet 28 disposed in a circle concentric with its drum, such ratchet 28 being sunk in the surface of the flange, as more clearly indicated in Fig. 3, which shows perspectively a fragment of the winding-drum 17, the flange 16 and the upwardly projecting portion of the shaft 9 which are similar to corresponding parts of shaft 10.

Pivottally disposed in each of two oblong holes 29 and 30 are a pair of pawls 31, 31, 80 the pawls 31, 31 in the holes 29 being adapted to engage with the ratchet 28 of the flange 16 while the pawls 31, 31 in the hole 30 may engage with ratchet 28 of the flange 26 and each pair of the pawls 31, 31 may be 85 raised, if desired, and disengaged from its ratchet 28 by a string 32 that may be held by one's hand or tied to a convenient fixed object not shown, Fig. 6 shows by a perspective view the form of a pawl 31 whereon the projection 33 serves for connecting 90 with said string 32, the slot 34 being adapted to receive a pivot (not shown) and the holes 35, 35 serve to receive a pin (not shown) that may confine such pivot within said 95 slot 34 whereby the pawls 31, 31 may swing on such pivot.

The upwardly projecting portions of the shafts 9 and 10 are alike in form and dimensions, which form is more clearly illustrated in Fig. 3, wherein the shaft 9 in its uppermost squared portion 36 is provided on its opposite sides with slots 37, 37 of semi-circular cross-section while its cylindrical portion is provided with a vertical 105 slot 38 as shown.

Upon the cylindrical portion of shaft 9 that projects above the top-plate 12, as shown in Fig. 1, there is disposed a gear-wheel 39 and above it a gearwheel 40 which 110 gearwheel 40 is adapted normally to rotate freely on and around said shaft 9 while said

gearwheel 39 is prevented from turning on said shaft 9 by a feather 41 secured in the boring of said gearwheel 39 said feather 41 projecting within the vertical slot 38. Each 5 of the gearwheels 39 and 40 is provided with holes 42, 42, 42, 42, said holes 42 in the gearwheel 39 being disposed to register with the corresponding holes 42 in the gearwheel 40 whereby said gearwheels 39 and 40 may be 10 locked to revolve together by inserting plug 43 of the form shown in Fig. 4. Upon the cylindrical portion of the shaft 10 above said top-plate 12 is mounted normally to turn freely thereon a gearwheel 44 and above 15 said gearwheel 44 is removably mounted a larger gearwheel 45 which is prevented from turning on said shaft 10 by a feather 41 which engages with the slot 38. The larger gearwheel 45 and the smaller gearwheel 44 20 are each provided with holes 42 disposed like the holes 42 in gearwheels 39 and 40 whereby the plug 43 may lock the gearwheels 44 and 45 together to be turned by the shaft 10. The pitch diameters of the 25 small gearwheel 40 and the large gearwheel 45 and their relative positions are such as to cause their respective teeth properly to mesh during their rotation, while the larger gearwheel 39 and the smaller gearwheel 44 30 are likewise adapted to engage with each other in their rotation.

Upon the squared portion 36 of each of the shafts 9 and 10 is mounted a disk 46 provided with a hub 47 through which hub 47 35 extend holes 48 disposed to register with the semi-circular slots 37 disposed on opposite sides of the squared portion 36 within which holes may be disposed key-pins 49, as shown in cross-section in Fig. 1, whereby the disk 46 40 may be securely fastened to the squared portion 36. The disks 46, 46 are similar in all respects so that a sweep 50 may be attached to either one or the other of said disks 46, 46 as may be desired, in the practical 45 operation of the winch.

The sweep 50 may be attached to one of said disks 46 by means illustrated in Fig. 1 and in Fig. 8 wherein a flat plate 51 is riveted to the underside of the sweep 50 by rivets 50 52 and upon the under surface of said plate 51 are secured brackets 53 of a size, form and disposition to adapt them to engage with disk 46, in the manner shown in Fig. 1. Extending downwardly through the sweep 50 55 and through the plate 51 is a hole disposed to register with a hole 54 disposed in the top end of each of the squared portions 36 of the shafts 9 and 10, within which holes may be disposed a king-pin 55.

As more clearly shown in Fig. 8, brackets 60 56 are disposed on each side of the sweep 50 within which are pivoted dogs 57 of a form illustrated in Fig. 7, whereby each may be disposed, as shown, to engage with the side 65 of one of the four holes or recesses 58 dis-

posed at equidistant points near the outer edge of the upper side of the disk 46.

Each of the dogs 57 is articulated by means of a connecting rod 59 with the end of a lever 60 which is pivoted by pivot 61 70 to the top surface of the sweep 50 as shown, whereby when said lever 60 is disposed in a direction parallel with the lengthwise direction of the sweep 50, as shown in Fig. 8, then the two dogs 57 will be free from contact 75 with the disk 46, but if the handle 62 of said lever 60 be moved sidewise toward the right-hand, then the left-hand dog 57 will be lowered to fall into one of the recesses 58 while the right-hand dog 57 will be raised 80 higher from the disk 46 in an obvious manner; and manifestly if the handle 62 be moved toward the left-hand a directly contrary effect upon the dogs 57 would result. Thus the sweep 50 by its associated devices 85 described may be operated to turn in either direction, as required, or it may be caused to remain stationary while the shaft to which it is attached is turning in response to a movement of the cable 20. 90

Upon the inner side of the stud 13 we have provided a saddle 63 that is slidably adjustable vertically by means of adjusting screws 64 said saddle 63 being adapted to serve as a seat within which to dispose a 95 rope sling 65 whereby the winch may be secured in a fixed position by fastening said sling 65 to some fixed object, as to a stump 66, and when the winch is so fastened to a fixed object the saddle 63 may be adjusted vertically by adjusting screws 64 to a desired point on stud 13. 100

Manifestly a winch embodying our invention as described, is adapted to be operated to move light objects at a high rate 105 of speed or to move very heavy bodies at a low rate of speed, for instance, a single cable might be connected on the drum of the shaft 10 with an end attached to a light object to be moved, then if the plug 43 be 110 inserted through holes 42 of gearwheels 44 and 45 to lock them together a rotation of the shaft 9 by a movement of the sweep 50 would communicate motion to the larger gearwheel 39 and the smaller gearwheel 44 115 to cause the shaft 10 with its drum to rotate at twice the speed of shaft 9, said larger gearwheel 39 being twice the size of said smaller gearwheel 44. Or, a single cable might be attached to the drum 17 of shaft 9 120 and to an object to be moved, and the plug 43 removed from the winch, in which case said drum 17 would be turned independently of the drum of shaft 10 and at the same speed as that of the movement of the sweep 50. 125 Or, the sweep 50 might be transferred to the shaft 10 with the plug 43 disposed to lock gearwheels 44 and 45 together, then a movement of the sweep 50 would cause the drum 17 to rotate at half the rate of speed of shaft 130

10 since the smaller gearwheel 44 would then be the driving gearwheel and would act to engage with the larger gearwheel 39. Or, as shown in Fig. 1, a pulley-block 22 disposed within the loop of a cable might 5 be attached to an object, as a stump 25, and one end of such cable be connected to the drum 17 while its other end is connected to the drum of shaft 10 and wound thereon in the same direction, the sweep 50 being attached to shaft 9 and the plug 43 disposed to lock gearwheels 39 and 40 together whereupon if the sweep 50 be turned the shaft 9 would revolve twice as fast as the 10 shaft 10 by reason of the relative sizes of the driving and driven gearwheels, but in a different direction of rotation to cause the cable 20 to be wound upon the drum 17 at a greater rate of speed than it would be un- 15 wound from the other drum, thus to move slowly to shorten the loop of the cable 20 to move with great power the object acted upon.

Under some conditions of operation the 20 gearwheels 39 and 44 might be dispensed with in which case the gearwheel 40 would have to be fastened upon the shaft 9 in a fixed circumferential position.

Other obvious changes with relation to the 25 different positions of the several parts of the winch may be made to serve different requirements.

Of course the form and size of parts of the structure may be varied and any minor 30 modifications may be made in the winch described without departing from the spirit of our invention.

What we claim is:

1. In a winch of the class described, the 40 combination with a supporting frame, comprising a bed plate and a slotted top plate, of two separate shafts rotatable in bearings within said frame, a winding-drum mounted upon each of said shafts, ratchet teeth 45 provided in the top of said drums, double pawls pivotally secured to said frame and arranged to engage said ratchet teeth, a gearwheel removably mounted upon each of said shafts and provided with means for releasably securing it in a fixed circumferential 50 position thereon, another gearwheel mounted on each of said shafts adapted normally to rotate freely thereon, means for releasably locking together on each of said 55 shafts the two gearwheels disposed thereon, the said gearwheels of one of said shafts each being disposed and adapted to engage with a different one of the gearwheels of the other of said shafts, the loose gearwheel 60 on one shaft being in mesh with the fast gearwheel on the other and interchangeable means for communicating rotary motion to one or the other of said shafts as may be desired.

65 2. In a winch of the class described, the

combination with two winding-drum shafts disposed vertically each to rotate in bearings in a supporting frame, the lower one of such bearings being formed to engage with the end surface as well as with the peripheral 70 surface of its shaft while a portion of each of said shafts projects upwardly from the top of said frame, said upwardly projecting portion being provided with a squared end, of a winding-drum mounted upon each of 75 said shafts, means for communicating rotary motion to either of said shafts as desired, said means consisting of a disk having recesses in its top surface and provided with a squared socket that is adapted to fit the 80 squared end of one of said shafts, a sweep provided with brackets to engage said disk, a king pin to secure said sweep to one of said shafts, pawls associated with said sweep and arranged to engage with the recesses 85 in said disk to move said disk when said sweep is moved, a cable, one of whose ends is connected to one of said drums while its other end is connected to the other of said drums, a gearwheel mounted and releasably secured on one of said shafts to revolve therewith, another gearwheel of different diameter securely mounted on the other of said shafts to revolve therewith, said gearwheels being arranged to engage with 90 each other whereby when one of said drums is rotated the other of said drums shall revolve at a different rate of speed.

3. In a winch of the class described, the combination with two winding-drum shafts 100 disposed to rotate in suitable bearings in a supporting frame comprising a bed plate and a slotted top plate and provided with squared upper ends, of a disk having recesses in its top surface, means for securing 105 said disk to said shafts, a sweep, a king pin to secure said sweep to said shaft, pawls associated with said sweep and arranged to engage with the recesses in said disk to move said disk when said sweep is moved, a winding-drum mounted upon each of said shafts, 110 a toothed ratchet associated with each of said winding-drums, pawls pivotally mounted in said supporting frame and extending through the slots in said top plate to engage with said toothed ratchets of said winding-drums, two gearwheels of different sizes releasably mounted on each of said shafts, the larger gearwheel of each shaft being adapted to engage with the smaller gearwheel of 115 the other shaft while one of the gearwheels of each shaft is releasably fastened thereon and the other gearwheel of each shaft is free to revolve thereon, and releasable means for locking together the two gearwheels of 120 either shaft.

4. In a winch of the class described, the combination with a frame, of winding-drum shafts disposed to rotate in suitable bearings in said frame, each of said shafts being 130

- provided with a squared upper end adapted to project above the top of said frame, transverse grooves provided in opposite sides of said squared upper end, a disk provided with recesses in its upper surface and formed with a squared socket that is adapted to fit over the squared upper ends of said shafts, grooves provided in opposite inside walls of said socket and adapted to register with the grooves in said squared ends of said shafts, perforations in said socket communicating with said grooves, pins fitted within said grooves to lock said disk on said shafts, a sweep associated with said disk and one of said shafts whereby such shaft may be turned, a winding-drum mounted upon each of said shafts and gearwheels to communicate motion from one of said shafts to others of said shafts.
- 5 20 5. In a winch, the combination with a drum-supporting frame embodying a vertically-disposed support parallel with the shaft of the winding drum of the winch, of a saddle fitting upon said support and vertically-adjustable thereon, and adapted to receive and support an anchoring rope-sling.
- 15 25

6. In a winch of the class described, the combination with a frame, of two separate shafts disposed to rotate in separate bearings in said frame, each of said shafts having a squared top end adapted to project above said frame, a disk provided with recesses in its top surface and having a socket adapted to fit over the squared top end of one of said shafts, a sweep pivotally secured to the top of one of said shafts, pawls associated with said sweep and adapted to engage with said recesses in the top surface of said disk to lock said sweep to said disk, a lever connected with said pawls whereby said pawls may be raised out of engagement with said recesses, winding-drums mounted on said shafts and gearwheels arranged to communicate motion between said shafts.

In witness whereof, we hereunto subscribe our names this thirtieth day of December, A. D. 1912.

GEORGE C. CARD.
WILLIAM MYERS.
